UNITED STATES PATENT OFFICE.

FLOYD BAKER, OF CICERO, ILLINOIS, ASSIGNOR TO SEARS, ROEBUCK & CO., OF CHICAGO, ILLINOIS, A CORPORATION OF NEW YORK.

IRONING TABLE.

Application filed October 17, 1921. Serial No. 508,181.

To all whom it may concern:

Be it known that I, FLOYD BAKER, a citizen of the United States, residing at Cicero, in the county of Cook and State of Illinois, have invented a new and useful Improvement in Ironing Tables, of which the following is a specification.

My invention relates, more particularly, to improvements in household ironing-tables of the folding type, namely of the type comprising an ironing-board proper and a supporting leg structure formed of members adapted to be folded into compact condition relative to the ironing-board proper, to permit of the ironing-table being stored away in relatively small space; my primary objects being to provide a novel, simple and economical structure of ironing-table of the general character stated which will present a high degree of rigidity, and the parts of which may be readily manipulated to condition the structures for use or for storage.

Referring to the accompanying drawings:

Figure 1 is a view in side elevation of an ironing-table constructed in accordance with my invention, the table being shown in condition for use. Figure 2 is a bottom plan view of the construction of Fig. 1, showing it in folded condition; and Figure 3, a broken view in side elevation of the construction in the condition shown in Fig. 2.

The particular illustrated embodiment of my invention comprises an ironing-board proper, represented at 4, this board being of any suitable shape such as that commonly provided in constructions of this general character, and represented in Fig. 2. The structure for supporting the board 4 at the desired elevation above the floor on which it would be supported comprises, in the particular embodiment shown, three frame-like members 5, 6 and 7. The member 5, which is shown as formed of two side bars 8 connected together at their lower ends by a cross-bar 9 and between their ends by a cross bar 10, is pivotally supported at its upper end on the ironing board proper 4 adjacent the left hand end of this board in the drawings. The pivotal connection of the member 5 with the board, as stated, is shown to be through the medium of pins 11 which extend through the bars 8 and into the ends of a cross-piece or cleat 12 secured to the under side of the board 4 to extend transversely thereof. The member 6 is formed of a pair

of bars 13 connected together by cross-bars 14 and 15. The frame 6 extends within the confines of the bars 8 relative to which latter they are pivoted, the pivotal connection shown being between the bars 13 and the cross-bar 10. The cross-bar 10 is shown as reduced in diameter at its opposite ends where it extends through the bars 8 and 13, it being preferred that the bars 8 be rigidly connected with the cross-bar 10 as by nailing them thereto. The frame member 7 is formed of a pair of bars 16 rigidly connected together at one end of the frame by a cross-bar 17 and pivotally connected at the opposite end of the frame with a cross-bar, or cleat 18, secured to the under side of the board 4 to extend transversely thereof, adjacent the end of the board opposite that provided with the cleat 12, the pivotal connection of the frame 7 with the cleat 18 being through the medium of pins represented at 19 which pass through the members 16 and into the ends of the cleat 18. The frame 7 is of such size that it extends within the confines of bars 13 when the parts are folded to the positions shown in Figs. 2 and 3.

The upper surfaces of the bars 8 between their free ends and the cross-bar 10, are recessed as indicated at 20 to form seats for the ends of the cross piece 17 which extend beyond the sides of the frame 7 into overlapping position relative to the bars 8.

In accordance with the preferred embodiment of my invention, the frame structures referred to are preferably interconnected to facilitate the conditioning of the structure for use and the folding of the same into compact condition for storage, the interconnecting means shown comprising a pair of rods 21 pivotally connected at their opposite ends, as indicated at 22 and 23, to the side bars of the frames 6 and 7. By preference these rods are bent into the form shown to present the laterally, oppositely-extending, portions 24 and 25 which extend through openings in the side bars 13 and 16 respectively and are upset at their outer ends against washers 26 surrounding them, to form the pivotal connections referred to.

The parts of the construction are illustrated in Fig. 1 in the positions they assume in use, the table being supported at the lower ends of the frames 5 and 6 upon the floor, the floor line being represented at 27, the cross-piece 17 being seated at its ends in the

recesses 20 in the members 8, and the cross-piece 15, which is preferably of rectangular shape in cross-section, abutting a cleat 28 secured to the under side of the board 4 to extend crosswise thereof.

The arrangement of the parts as shown and described is such that the structure, when conditioned for use, as shown in Fig. 1, presents a high degree of rigidity not only rendering it stable, but also preventing objectionable give to the board during the ironing operation and avoiding the travel or hitching of the table along the floor.

When it is desired to fold the parts of the table into compact condition (Figs. 2 and 3), this may be done by the operator first swinging the frame 5 a slight distance in a direction away from the board 4, and thereupon swinging the frame 6 in counter-clockwise direction in Fig. 1 to cause it to extend substantially parallel with the frame 5, and substantially parallel with the board 4, the rod connections between the frames 6 and 7 causing the frame 7 to swing to a position in which it extends substantially parallel with the board 4 in thus operating the frame 5.

To condition the table for use, the operator by grasping with one hand the end 30 of the board 4 adjacent that to which the frame 7 is pivoted, and grasping the frame 5 with his other hand and swinging the latter away from the table top, causes the frame 6 to swing therewith in the same direction, 35 and as soon as the frame 5 has been moved to a position in which the frame 6 may be swung into a position adjacent the cleat 21, the frame 6 is swung into engagement with this cleat, the operator at the same time 40 swinging the frame 5 toward the board 4. Thus operating the frames 5 and 6 automatically causes the frame 7 to swing away from the board and into a position in which the

ends of the cross-bar 17 extend into the recesses 20 of the frame 5.

While I have illustrated and described a particular construction embodying my invention, I do not wish to be understood as intending to limit it thereto as the same may be variously modified and altered without departing from the spirit of my invention.

What I claim as new, and desire to secure by Letters Patent is:

An ironing table comprising an ironing board, a supporting structure therefor comprising a plurality of members pivotally connected together between their ends, one of said members being pivotally connected at its upper end to said ironing board and extending in a downwardly inclined direction toward the opposite end of said board, said board being provided with a stop surface between said last-referred-to pivotal connection and the opposite end of the board, and the upper end of the other of said members engaging said stop surface in the extended position of said supporting structure, the one of said members which is pivoted to said board having a stop-forming portion, a member pivoted at its upper end to the board and adapted to engage at its lower end with said stop-forming portion, and a link structure operatively connecting said last-named member with the one of said first-referred-to members other than the one recited as pivotally connected at its upper end to said ironing board, to cause the said last-named member and the member with which it is connected, to move in unison, the whole being so constructed and arranged 70 that when the supporting structure is extended said last-named member engages said stop-forming portion and the one of said first-named members other than the one pivoted to said board, engages said stop surface

FLOYD BAKER.
